DRAFTING TABLE

Alfred William Faux and Russel Earl Helland, Toronto,
Ontario, Canada, assignors to Norman Wade Company
Limited, Scarborough, Ontario, Canada, a corporation of Canada

Filed May 6, 1965, Ser. No. 85,134

Term of patent 14 years

(Cl. D33—14)

We claim:

The ornamental design for a drafting table, as shown.
